UNITED STATES PATENT OFFICE

2,613,001

CARGO HANDLING APPARATUS FOR SHIPS

Burton M. Green, Ballston Spa, N. Y.

Application November 12, 1947, Serial No. 785,383

4 Claims. (Cl. 212—3)

1

My invention relates to improvements in cargo handling apparatus for ships, and particularly to a cargo handling derrick rig for use in loading cargo to and unloading cargo from the holds of a ship through the hatchways or other openings for the purpose of handling of cargo of any kind or description.

An object is to provide a cargo handling apparatus and derrick rig in combination with the usual cargo handling boom swingably mounted on a mast or Samson post or King post for transverse and lifting and lowering movement, which apparatus and rigging includes a cargo fall rigging for the boom, and a topping lift tackle rigging in combination with the outboard guy, from the mast or post to the boom and from said boom to a connection spaced outboard from the mast, so that when the derrick is in use, the boom under its own weight, or under the weight of the cargo load, will gravitate and swing toward an outboard position, whereby the necessary movement of the boom to carry the load from the hatch opening to the over-the-side position will be accomplished by the outboard guy, such movement being accomplished by gravitating swinging of the boom, and this swinging movement will be controlled by the inboard power guy or drag line for the purpose of slackening the boom outboard and retrieving it to the position over the hatch.

Another object is to provide a rigging of this character with which the boom is swung up or moved inwardly toward the mast or Samson post when swung in by the power control guy or drag line, and with which the boom is swung down or lowered as it moves to the outboard position so that a greater over-the-side extension of the boom is accomplished without adjustment of or attention to the topping lift tackle rigging, which minimizes the operation of the topping-lift winch.

A further object is to provide a combination topping lift and guy tackle which functions reciprocally so that when the boom is hoisted to its proper position it assumes a natural gravitational swing toward the outboard or over-the-side position when the controlling inboard guy is slackened off, the parts being capable of adjustment to vary the gravitational swinging force in accordance with the adjustments made in placing the deck or lower block of the outboard guy.

Still another purpose is to so construct and arrange the parts that the outboard or over-the-side swinging movement is induced by gravity, with the movement of the boom then readily controlled by a single inboard power guy drag line,

2

which also swings or retrieves the boom to its position over the cargo hatch opening by a single winch operation.

Another purpose is to so construct the parts that the running tackle rigging can be a gun-tackle, a luff-tackle, a two-fold purchase, a three-fold purchase, a four-fold purchase, or in fact any suitable rigging that may be found desirable or necessary; depending upon the conditions of use and the load to be handled and the purchase desired to be employed.

Yet another purpose of my invention is to provide apparatus of this character which can be readily installed and used in connection with derrick and boom and mast and post stretchers as now ordinarily installed and in use upon ships, derrick barges, lighters, and shore cranes, which may be stationary or movable, with only slight structural changes being required.

Yet another purpose is to provide an apparatus of this character in which the load carrying end of the derrick boom will lower gradually as the boom swings by gravity to the outboard or over-the-side position, and reversely the boom will top-up or be raised when swung inboard over the cargo hatch opening by the power control or retrieving guy.

Another purpose is to so construct and arrange the topping-lift purchase and the guy-tackle purchase for swinging the boom, that various types of running rigging can be employed depending upon the load to be handled, and the guy-tackle purchase rigging can be adjusted to give greater or less top-up and lowering movement of the boom, as well as to increase and decrease the gravitational pull tending to swing the derrick boom to the outboard position.

Another purpose is in the provision of rigging for a ship mounted with a cargo handling derrick of such character that the booms can be lifted up at sea, as long as the cargo fall is hooked onto the deck and the topping lift rigging is drawn taut, thus leaving the booms always in position for immediate use and made ready over a section of a cargo hatch opening where cargo is to be discharged or lowered, with no further adjustment of the boom being necessary.

Still another purpose is to provide a cargo handling apparatus for ships with which the running end of the combination guy and topping-lift tackle can be made fast, or can be connected with a suitable winch, and with which the parts and operations can be readily carried out by employment of a winch for the cargo fall rigging and a winch for the control drag line.

With the above and other objects in view, some of which will be apparent to those skilled in the art, and others of which result from the combination and arrangement of parts and the inter-related operation, my invention includes certain novel features of construction and combinations and arrangements and assemblies of parts which will hereinafter be set forth in connection with the drawings, and then pointed out in the claims.

In the drawings:

Figure 1 is a transverse fragmentary sectional view through the forward part of a ship showing an embodiment of my invention with a derrick boom mounted upon a Samson post.

Fig. 2 is a fragmentary top plan and deck view of the installation shown in Figure 1.

Fig. 3 is a fragmentary detailed view of a gooseneck boom mounting adaptable for use with my invention.

Fig. 4 is a fragmentary detailed view showing a saddle structure adaptable to receive and hold the boom when not in use.

Fig. 5 is a fragmentary deck and plan view illustrating an embodiment of my invention with a single mast derrick structure.

Fig. 6 is a view similar to Figure 1, showing another embodiment.

As disclosed in Figures 1 and 2, the boom 1 is mounted for up and down and for lateral swinging movement on the mast or Samson post or King post, or other suitable upright post construction 2, and in the present instance this support 2 can be taken as a Samson post, two such posts being usually provided, as disclosed in Fig. 2. Fig. 2 illustrates a ship structure, the hull of which is indicated at 3, in the bow portion, and then shows the Samson post 2 as mounted forward of No. 1 hatchway, as indicated at 4. Of course, it will be understood and appreciated that my invention can be embodied with a single mast, or a Samson post, or King post, either forward or astern of a hatch opening over which the crane or derrick structure is to operate. Further, while I have herein particularly illustrated my invention in connection with a derrick upon a ship, it is to be understood and appreciated that the present invention is equally capable of use upon substantially any derrick construction, ashore or afloat, where it may be desired to secure or accomplish an increased outboard movement or swing of the top of the boom from one location to another; and where it is desirable that movement in one direction be accomplished through employment of a drag line, and movement in the other direction be resultant from gravity forces due to the weight of the boom when either loaded or unloaded.

In Fig. 3, I have illustrated a gooseneck mounting for the boom 1 so that this boom can have substantially 180 degrees of transverse swing with respect to the mast or post 2. As here disclosed, a bracket 5 carried by the post or mast 2 has journaled therein a portion of the gooseneck bearing member 6, and the foot of the boom 1 has a bearing portion 7 mounted in the gooseneck bearing portion 6 for the up and down swinging movement, horizontal swinging movement being accommodated by the pin 8 turning within the bearing portion 5. A block 9 is also swingably mounted by the bearing portion 5, and is thus conveniently disposed to receive the load line 10 constituting part of the load tackle and preferably extending over a sheave 11 at the top of the boom and provided on its depending end with a cargo hook 12. The bearing is prefer-

ably offset outboard at an angle of about 30 degrees from the center line to thus allow full outboard swing of boom 1.

With the boom 1 mounted in the manner set forth, this boom is capable of up and down swinging movement to an angle of substantially 90 degrees, or substantially from the horizontal to the perpendicular, and is also permitted horizontal swinging movement throughout substantially 180 degrees from its inboard to its over-the-side or outboard position. Movement of the boom is retrieved by an inboard power guy 13, which is run over a block or sheave 15, and has its running end disposed in position to be taken in or payed out or slackened off, by a suitable winch 16.

The load line or cargo fall 10 can be hauled or slackened in any desired manner, and in the present instance I have illustrated a winch 17 as being positioned to handle the running end of this cargo fall 10. It is preferable that the winch 17 be of the general type of winch, electric or steam, as now installed upon vessels handling general cargo.

In the embodiment illustrated in Figure 1, the boom 1 has a block or sheave 18 receiving a running part of cable or rope 19 constituting the topping-lift tackle, and sheaves 20 and 21 are provided on the head or peak of the Samson post or mast 2 for running parts of cable 19 so that the topping-lift tackle is a gun-tackle. One running portion of this cable 19 is lead through the sheave 20 and down the mast or Samson post 2, and is then lead through suitable sheaves and to a winch 22. The pendant cable 23 is connected with the peak of the boom to serve as part of a guy tackle opposite the power guy or drag line 13. A sheave 24 is becketed to this pendant cable 23. The running portion of cable 19 running through sheave 21 is carried downwardly and through a heel block, or deck outboard guy block 25, then back up through sheave 24, and is returned to and is becketed on the heel block 25. This heel block 25 is connected with the elevated part 26, or is connected in an eye 27 located on the deck or other suitable portion of the ship, on the outboard side and spaced away from the mast 2. As indicated at 28, in Fig. 2, several eyes can be provided at different distances of spacing from the post or mast 2, and thus the heel block 25 can be connected at greater or lesser distance outboard from the mast 2.

With the cable 19 running through the blocks 24 and 25, a gun-tackle purchase is arranged to fall from the pendant cable 23, and to serve as an outboard guy tackle. As stated, the block 25 can be connected at the brace of the forecastle head, at the rail, or any other suitable point upon the deck, and in this way connection of the guy tackle purchase can be disposed closer to or further from the foot of the mast or post 2.

The winch 22 is preferably of the screw or brake or ratchet type so that the guy tackle can be adjusted to elevate the head or peak of the boom to dispose the cargo hook 12 in proper relation with respect to the hatch opening 4, and through the power drag line 13 the cargo boom can be moved in, as shown by the dotted lines in Fig. 2, or to the full line position of Figure 1. The load cable 10 can then be used to secure and lift a load from the hold, or can be slackened off to lower a load. When it is desired to have the boom move to the outboard position, the drag line 13 is slackened off from the winch 16, and the outboard spacing of the heel block 25 of the guy tackle will cause the boom

to move by gravity toward and to its outboard position, to a location of maximum boom extension or reach, as disclosed in dotted lines in Figure 1, and in full lines in Fig. 2. This gravity pull is accomplished through the weight of the boom, and of the load if the boom is carrying cargo, exerting pull upon the topping-lift tackle, and as the topping lift tackle lengthens, this will burden the outboard guy tackle so that as the boom is swung by gravity force to its outboard position, the peak of the boom is at the same time lowered to thus give the desired boom reach. Further, since a pier or wharf floor or a lighter deck is ordinarily at a somewhat lower level than the hatchway coaming, as the boom swings out by gravity the load, generally indicated at 29 in Figure 1, will be lowered, and as the boom is retrieved through the drag line 13, the peak of the boom will be raised and the load 29 will be sufficiently elevated to clear the deck and rail and hatch coaming of the ship. With this arrangement, in which the outboard guy moves in conjunction with the topping-lift, which imposes the pulling power on the guy, it is not necessary to have another outside guy; only the inboard retrieving power guy or drag line is necessary to complete the necessary swinging movement of the derrick. As stated, the outboard drag line tackle and the topping-lift tackle will automatically run and adjust to lower the peak of the boom 1, and consequently increase the outboard or over-the-side reach of the boom and at the same time lower the load as suspended by the cargo hook 12.

Ordinarily, it has been found expedient to lower the cargo booms and support these on rests in substantially horizontal position when the booms are not in use or the ship is at sea or traveling; and, I have found that with my present rigging this lowering of the booms is not required, since the booms can be secured to remain in place and to prevent moving. Further in this respect, as shown in Figs. 4 and 6, for convenient securing on the usual bridge 30 extending across between the Samson posts 2, I provide a hook-like cradle 31 into which the boom 1 can be fitted when raised to a position adjacent to the posts or masts 2. A locking toggle and pin can be provided at 32, or other securing means can be employed to hold the boom in the saddle 31, and this will allow the combined topping-lift and outboard guy tackle to be slackened off, and the boom will be secured against shifting or other movement. Thus, it is possible to keep the boom rigged and in an upright position where it is ready for almost instantaneous use.

While the disclosure has been particularly related to a starboard derrick structure including a starboard Samson post and boom, with the boom working over the starboard side of the ship, it is to be understood and appreciated that a similar adaptation can be employed on the port side Samson post or King post or mast. Thus, it may be found necessary for the winches 16 and 17 to be used interchangeably.

In the embodiment of my invention illustrated in Fig. 5, the ship hull is generally indicated at 33, and a derrick mast 34 is provided substantially at the center line of the hull aft of the cargo hatch 35. The boom 36 is here disclosed as rigged for use over the starboard side, and a plurality of deck rings are disclosed at 37, at different locations, so that the heel block, or deck outboard guy block, 38 can be disposed at dif-

ferent adjusted distances transversely with respect to the mast, and to positions forward and aft of a line taken transversely through the mast. Thus, it is possible to adjust the position of the heel block 38, so that greater or lesser pull will be exerted through the outboard guy tackle.

With the adaptation illustrated in Fig. 6, the arrangement of the parts is substantially similar to the previously described embodiments, and the boom 39 is movable with respect to a post or mast 40. The topping-lift 41 is here shown as a double purchase tackle, and the outboard guy tackle 42 is illustrated as a luff-tackle. In this connection, it will be understood and appreciated that various arrangements can be made of the topping-lift tackle and the outboard guy tackle, to include gun-tackle rigging or luff-tackle, 2-fold purchase rigging, 3-fold purchase tackle, 4-fold purchase rigging, or any suitable combination of two of these riggings. Thus, it will be possible to accomplish many different arrangements and movements and to vary the purchase forces exerted by the topping-lift tackle and the outboard guy tackle.

The advantages gained by my improved combination of topping-lift and outboard guy tackle is resultant from the reciprocal take-up and running out of the two tackles as the boom is swung inboard through the drag line or inboard guy tackle, and is permitted to swing outboard to its over-the-side position by gravity as the inboard drag line is slackened off, and it will be seen that when the boom is hoisted to its proper position it assumes a natural gravitational swing toward the outboard deck block through the weight of the cargo boom or a load held on the cargo hook. The swinging movement of the boom is controlled by slackening off the inboard power guy or drag line, and the boom is retrieved by this inboard guy to be swung back to its position over the cargo hatch by use of a single winch, and this single winch is operated substantially only 50 percent of the time. It will of course be appreciated that no Burton tackles or guys are necessary to hold the boom substantially or to swing the boom in connection or conjunction with the other cargo booms or in connection with guy booms.

Outboard movement of the boom is also by gravity and inboard movement also by power. It will thus be appreciated that my invention eliminates the old or present style of rigging including rope tackle guys and preventor guy wires, which are used in maintaining a fixed position of a cargo boom with a Burton rig. Thus omission of the usual restraining tackles will be appreciated in the advantage of winch operation.

One winch is operated to lift the load and hold it on the cargo hook, while the adjacent winch is used to swing the boom inboard and to slacken off the inboard drag line for controlling the boom in its outboard movement. Of course, a third winch can be used for controlling the combination topping-lift and outboard guy line tackle for the purpose of controlling the boom extension over the hatchway when handling heavy lifts, or this tackle can be adjusted manually and made fast to suitable chocks or fastenings. This third winch for controlling operation of the topping lift assembly will of course save manual handling and labor while stowing cargo in the forward or after ends of a compartment when shifting from one cargo storage to another. In some cases, as especially with a vessel having cen-

ter masts located at the forward and after ends or hatches, the topping-lift and guy tackle assembly may be easily shifted to accommodate loading and unloading of cargo movements on either side of the ship, by simply lowering the boom to a horizontal position on its rest base and then effecting a change-over on the winches to accommodate the particular side on which the boom is to be used so that the power guy or drag line may be rove off of the winch on the opposite side.

Also, it will be seen that the winch movement in operation of the boom while handling cargo will be equal to only about half of the normal operation involved in the present riggings and boom operation and with the present style of fixed or stationary adjusted booms stayed or guyed in fixed position.

While I have shown and described only certain particular embodiments of my invention and have suggested only certain other possible embodiments, it will be appreciated that many variations in the tackle rigging and purchase arrangements can be made calculated for the stress on the topping-lift and the outboard guy tackle, and that the swinging leverage or force exerted by the tackle can be varied by different arrangements of rovings, and by different placement of the heel or deck block of the outboard guy tackle.

The above shown and described embodiments are intended only to be illustrative of possible uses of my invention, and it will be appreciated that many changes and variations can be made in the particular connections and tackle riggings, to suit different instances and conditions of use, without departing from the spirit and scope of my invention.

I claim:

1. A cargo handling derrick apparatus comprising with a supporting structure such as a ship deck having an upstanding cargo mast with a cargo boom swingably mounted at one end on the lower part of the mast for up and down swinging lifting movement of the outer end and for transverse swinging movement over the ship deck and to positions with the outer end laterally extending beyond the deck, a hoist cable on said boom with a hoist end depending from the outer end of the boom and a hauling end extending to and available upon the deck, a cable pulley on the outer portion of the boom, a pair of cable pulleys on the upper part of the mast, a deck cable pulley connected on the deck at a location spaced outwardly laterally from the lower part of the mast, a rigging cable connected with the outer end of the boom extending through said deck cable pulley and then through one of the pair of cable pulleys and through the cable pulley on the outer end of the boom and then back through the other cable pulley of the pair and then downwardly with a hauling end extending to and available upon the deck, and an inboard control guy cable connected at one end to the outer end of the boom and having a hauling end extending to and available upon the deck.

2. A cargo handling derrick apparatus for a ship having a cargo mast upstanding from the ship deck with a cargo boom swingably mounted at one end on the lower part of the mast for up and down swinging lifting movement of the outer end and for transverse swinging movement of the outer end over the ship deck and to positions with said outer end laterally extending beyond the deck, a hoist cable on said boom with a hoist end depending from the outer end of the boom

and a hauling end extending to and available upon the ship deck, a cable pulley on the outer portion of the boom, a pair of cable pulleys on the upper part of the mast, a deck cable pulley connected on the ship deck at a location spaced outwardly laterally from and forwardly with respect to the lower part of the mast, a rigging cable connected with the outer end of the boom extending through said deck cable pulley and then through one of the pair of cable pulleys on the mast and through the cable pulley on the outer part of the boom and then back through the other cable pulley of the pair on the mast and downwardly along the mast with the hauling end extending to and available upon the deck of the ship, and an inboard control guy cable connected at one end to the outer portion of the boom and having a hauling end extending to and available upon the deck of the ship.

3. A cargo handling derrick apparatus for a ship having a cargo mast upstanding from the ship deck with a cargo boom swingably mounted at one end on the lower part of the mast for up and down swinging lifting movement of the outer end and for transverse swinging movement of the outer end over the ship deck and to positions with said outer end laterally extending beyond the deck, a hoist cable on said boom with a hoist end depending from the outer end of the boom and a hauling end extending to and available upon the ship deck, a cable pulley on the outer portion of the boom, a pair of cable pulleys on the upper part of the mast, a deck cable pulley connected on the ship deck at a location spaced outwardly laterally from and forwardly with respect to the lower part of the mast, a rigging cable connected with the outer end of the boom extending through said deck cable pulley and then through one of the pair of cable pulleys on the mast and through the cable pulley on the outer part of the boom and then back through the other cable pulley of the pair on the mast and downwardly along the mast with the hauling end extending to and available upon the deck of the ship, an inboard control guy cable connected at one end to the outer portion of the boom and having a hauling end extending to and available upon the deck of the ship, and plurality of deck eyes located at various spacing with respect to the lower part of the mast for adjustable connection and positioning of the deck cable pulley.

4. A cargo handling derrick apparatus comprising with a supporting structure such as a ship deck having an upstanding cargo mast with a cargo boom swingably mounted at one end on the lower part of the mast for up and down swinging lifting movement of the outer end and for transverse swinging movement over the ship deck and to positions with the outer end laterally extending beyond the deck, a hoist cable on said boom with a hoist end depending from the outer end of the boom and a hauling end extending to and available upon the deck, a cable pulley on the outer portion of the boom, a pair of cable pulleys on the upper part of the mast, a deck cable pulley connected on the deck at a location spaced outwardly laterally from the lower part of the mast, a rigging cable connected with the outer end of the boom extending through said deck cable pulley and then through one of the pair of cable pulleys and through the cable pulley on the outer end of the boom and then back through the other cable pulley of the pair and then downwardly with a hauling end extending to and available upon the deck, an inboard control guy

cable connected at one end to the outer end of the boom and having a hauling end extending to and available upon the deck, said cargo boom being movable to an upright position adjacent to the cargo mast when not in use, and cradle means carried by the upper part of the mast to receive the outer end of the boom in such raised position when not desired for use.
